UNITED STATES PATENT OFFICE.

HARRY RUDGINSKY, OF BOSTON, MASSACHUSETTS.

DESIGN FOR A RESILIENT TIRE.

Application filed May 9, 1924. Serial No. 9,534. Term of patent 14 years.

To all whom it may concern:

Be it known that I, HARRY RUDGINSKY, a citizen of the United States, residing at Boston, in the county of Suffolk and State of Massachusetts, have invented a new, original, and ornamental Design for Resilient Tires, of which the following is a specification, reference being had to the accompanying drawings, forming a part thereof.

In the drawings:

Figure 1 is a plan view looking upon a section of a tire showing my new design; and

Figure 2 is a longitudinal section on the line 2—2 of Figure 1.

I claim:

The ornamental design for a resilient tire, as shown.

HARRY RUDGINSKY.
